BAG

Claude E. Hayward and Edward S. Gorton, Mobile, Ala., and James W. Girvin, East Peoria, Ill., assignors to Bemis Bro. Bag Company, St. Louis, Mo., a corporation of Missouri

Application May 28, 1956, Serial No. 587,777

8 Claims. (Cl. 229—57)

This invention relates to bags, and more particularly to a pasted closure construction for a multi-ply bag.

The invention is hereinafter described particularly as it pertains to a bag having an inner ply consisting of two layers of paper laminated together by asphalt, and one or more outer plies of plain paper such as natural kraft paper. If such a bag is made with a conventional pasted closure in which there is adherence only of the asphalt-laminated ply to plain paper, there is a possibility that the closure may fail, due for example to embrittlement of the asphalt in the asphalt-laminated inner ply in cold weather. The principal object of the invention is the provision of an improved pasted closure construction for a bag of this class featured by substantial direct adherence of plain paper to plain paper, instead of adherence only of the asphalt-laminated ply to plain paper, to eliminate the possibility of failure of the closure due to embrittlement of the asphalt. It will be understood that the invention is not limited to a bag in which the inner ply consists of two layers of paper laminated together by asphalt, but is applicable to a bag with an inner ply of any material which is of such nature as to make it desirable to provide for substantial direct adherence of plain paper to plain paper in the closure to avoid failure of the closure. For example, the invention is applicable to a bag in which the inner ply consists of a single layer of paper impregnated with asphalt, or consists of a wax-coated paper, or consists of sheet plastic material such as cellophane, polyethylene or the like. Other objects and features will be in part apparent and in part pointed out hereinafter.

The invention accordingly comprises the constructions hereinafter described, the scope of the invention being indicated in the following claims.

In the accompanying drawings, in which several of various possible embodiments of the invention are illustrated.

Fig. 1 is a view of the lower portion of a bag tube having an inner ply consisting of two layers of paper laminated together by asphalt and an outer plain paper (natural kraft) ply, the tube being shown with a closure of this invention partially formed;

Fig. 2 is a greatly enlarged section taken on line 2—2 of Fig. 1;

Fig. 3 is a view similar to Fig. 1 showing the pattern of paste applied to the closure;

Fig. 4 is a view similar to Figs. 1 and 3 showing the completed closure;

Fig. 5 is a greatly enlarged section taken on line 5—5 of Fig. 4;

Figs. 6—10 are views corresponding to Figs. 1—5, respectively, illustrating a modification.

Corresponding reference characters indicate corresponding parts throughout the several views of the drawings.

Referring to Fig. 1, there is indicated at 1 a flat bag tube. Only the lower portion of the tube is shown. As illustrated, the tube is a two-ply tube, the inner ply being

2

designated 3 and the outer ply being designated 5. As appears in Figs. 2 and 5, the inner ply 3 consists of two layers 7 and 9 of paper (such as kraft paper) laminated together by asphalt 11. The outer ply 5 consists of a single layer of plain paper, such as kraft paper. While only one outer plain paper ply is shown for simplicity, it will be understood that the tube may have more than one outer plain paper ply. It may be a three-ply tube, for example, in which case it will have the inner asphalt-laminated ply 3 and two outer plain paper plies like 5.

Fig. 1 shows the lower portion of the tube with a diamond-fold type of closure partially formed. As is apparent from Fig. 1, the closure comprises inwardly directed end flaps 13 and first and second side flaps 15 and 17. The transverse edge of the portion of the inner ply 3 included in the side flap 15 registers with the transverse edge of the portion of the paper ply 5 included in the side flap 15 as indicated at 18. In accordance with this invention, the portion of the inner ply 3 included in the side flap 17 is provided with openings 19. These extend completely through layer 7, asphalt 11 and layer 9 of the inner ply. They do not extend through the paper ply 5 (see Fig. 2). They are arranged in a row adjacent the outer transverse edge 21 of the flap 17. Portions of the paper ply 5 indicated at 23 are exposed through the openings.

In forming the closure, adhesive (paste), designated A, is applied in a U-shaped pattern as shown in Fig. 3. This pattern consists of a stripe of adhesive 25 extending transversely across the side flap 17 adjacent its outer transverse edge 21 and stripes 27 extending from the ends of stripe 25 in lengthwise direction with respect to the tube over the end flaps 13. The stripe 25 is wider than the openings 19 and generally centered in respect to the openings. The first side flap 15 is folded over upon a transverse fold line 29 to overlie the end flaps 13. The portion of the paper ply 5 included in the folded-over first side flap 15 is on the outside of the flap, the entire outside of first side flap 15 being constituted by a portion 30 of the paper ply 5. The second side flap 17 is folded over upon a transverse fold line 31 to overlie the first. The portion of the paper ply 5 included in the folded-over second side flap 17 is also on the outside.

The inside of the folded-over second side flap becomes adhered to the outside of the folded-over first side flap, that is, to the portion of the paper ply 5 included in the first side flap. Those portions 23 of the portion of the paper ply 5 included in the second side flap which are exposed through the openings 19 are secured directly to the first side flap by the adhesive, even through this portion of ply 5 is on the outside. This direct adherence of the portions of the paper ply 5 included in the closure eliminates the possibility of failure of the closure as might otherwise occur due to embrittlement of the asphalt in the ply 3 in cold weather. In this respect, it is to be observed that if the portion of the asphalt-laminated ply 3 in the second side flap 17 were pasted to the first side flap 15 without adherence of the portion of ply 5 in flap 17 to flap 15, embrittlement of the asphalt would be apt to result in failure of the closure via separation of the layers of ply 3 or separation of the second side flap from the first.

Figs. 6—10 illustrate a modification in which the portion of the inner ply 3 included in the second side flap 17 is formed to expose a part of the paper ply 5 by having the outer transverse edge 33 of this portion spaced inward from the outer transverse edge 35 of the portion of the paper ply 5 included in side flap 17. The resultant exposed portion of the ply 5 is designated 37. The pattern 65 of adhesive (paste) A in this case is also U-shaped, consisting of a stripe 39 extending transversely across the side flap 17 adjacent its outer edge 21 and stripes 41 corre-

sponding to stripes 25. The stripe 39 overlaps the edge of the inner ply 3. The closure is completed in the same manner as above described. In the completed closure, the exposed portion 37 of the paper ply 5 in flap 17 is secured directly to the portion of the paper ply 5 in flap 15.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

We claim:

1. A closure construction for a bag of the type having an inner ply and at least one paper ply outside said inner ply, said inner ply comprising a material different from the paper ply and which is less desirable for closure adhering than paper, said construction comprising inwardly directed end flaps and first and second side flaps, the first side flap being folded over upon the end flaps and the second side flap being folded over on the first side flap, the transverse edge of the portion of the inner ply included in the first side flap registering with the transverse edge of the portion of the paper ply included in the first side flap so that the entire outside of the first side flap consists of a portion of the paper ply, the portion of the inner ply included in the second side flap being formed so that a part of the portion of the paper ply included in the second side flap on the outside of the inner ply is exposed toward the outside of the first side flap, a portion of said second side flap including said exposed part of the portion of the paper ply included therein being secured to the first side flap by adhesive.

2. A closure construction as set forth in claim 1 wherein the portion of the inner ply included in the second side flap is formed to expose part of the paper ply by providing openings in the inner ply extending completely through said inner ply but not extending through the paper ply.

3. A closure construction as set forth in claim 2 wherein the openings are arranged in a row adjacent the outer transverse edge of said second side flap.

4. A closure construction as set forth in claim 3 wherein the adhesive is applied in a pattern including a stripe of adhesive extending transversely across the second side flap wider than the openings and generally centered in respect to the openings.

5. A closure construction as set forth in claim 1 wherein the portion of the inner ply included in the second side flap is formed to expose part of the paper fly by having the outer transverse edge of said portion spaced inward from the outer transverse edge of the portion of the paper ply included in the second side flap.

5

6. A closure construction as set forth in claim 5 wherein the adhesive is applied in a pattern including a stripe of adhesive extending transversely across the second side flap adjacent its outer edge and overlapping said transverse edge of the inner ply.

7. A closure construction for a bag of the type having an inner ply consisting of two layers of paper laminated together by asphalt and at least one paper ply outside said inner ply, comprising inwardly directed end flaps and first and second side flaps, the first side flap being folded over upon the end flaps and the second side flap being folded over on the first side flap, the transverse edge of the portion of the inner ply included in the first side flap registering with the transverse edge of the portion of the paper ply included in the first side flap so that the entire outside of the first side flap consists of a portion of the paper ply, the portion of the inner ply included in the second side flap being formed so that a part of the portion of the paper ply included in the second side flap on the outside of the inner ply is exposed toward the outside of the first side flap, a portion of said second side flap including said exposed part of the portion of the paper ply included therein being secured to the first side flap by adhesive.

8. A closure construction for a bag of the type having an inner ply consisting of a composite paper-asphalt material and at least one paper ply outside said inner ply, comprising inwardly directed end flaps and first and second side flaps, the first side flap being folded over upon the end flaps and the second side flap being folded over on the first side flap, the transverse edge of the portion of the inner ply included in the first side flap registering with the transverse edge of the portion of the paper ply included in the first side flap so that the entire outside of the first side flap consists of a portion of the paper ply, the portion of the inner ply included in the second side flap being formed so that a part of the portion of the paper ply included in the second side flap on the outside of the inner ply is exposed toward the outside of the first side flap, a portion of said second side flap including said exposed part of the portion of the paper ply included therein being secured to the first side flap by adhesive.
